Primary Examiner — Nathaniel D. Buckner(74) *Attorney, Agent, or Firm* — Cislo & Thomas, LLP(57) **CLAIM**

The ornamental design for a battery case, as shown and described.

DESCRIPTION

FIG. 1 is a top perspective view of my battery case;

FIG. 2 is a front view thereof;

FIG. 3 is a rear view thereof;

FIG. 4 is a right side view thereof;

FIG. 5 is a left side view thereof;

FIG. 6 is a top view he of; and

FIG. 7 is a bottom view thereof;

FIG. 8 is a top perspective view thereof; and,

FIG. 9 is a bottom perspective view thereof.
